[57] CLAIM

The ornamental design for a foal feeder, as shown and described.

DESCRIPTION

FIG. 1 is a perspective view of a foal feeder embodying my design.

FIG. 2 is a front elevational view thereof.

FIG. 3 is an end elevational view thereof, the opposite end being a mirror image of the end shown.

FIG. 4 is a top view thereof.

FIG. 5 is a fragmentary cross sectional view taken on the line 5—5, of FIG. 4.

FIG. 6 is a fragmentary cross sectional view taken on the line 6—6, of FIG. 4.

Fig. 1.**Fig. 2.****Fig. 3.****Fig. 4.****Fig. 5.****Fig. 6.**
